WIRE GARMENT HANGER MAKING
MACHINE

William A. Scroggs, San Diego, Calif.

Application September 11, 1944, Serial No. 553,516

8 Claims. (Cl. 140—81.5)

1

My invention relates to a wire garment hanger making machine and the objects of my invention are:

First, to provide a machine which will produce wire garment hangers from straight lengths of wire of suitable size and character, by hand power, the machine being therefore suitable for use by anyone requiring a considerable quantity of hangers;

Second, to provide this machine at reasonable cost and of very simple design so that it is very easy to operate;

Third, to produce a machine which will produce a satisfactory hanger from a minimum length of wire and without any inherent weakness due to improper twisting;

Fourth, to provide a machine which will require a minimum of repair and maintenance and of such sturdy construction that the machine will give long term satisfactory performance.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part of this application in which:

Figure 1 is a top plan view of my invention showing a wire blank properly inserted into the machine ready for forming, and also indicating in dotted lines one position of the hand crank assumed during the subsequent forming operation; Fig. 2 is a front elevational view of my machine with the hand crank in the position assumed for wire blank loading; Fig. 3 is a top plan view of the left wire bending lever together with its roller supporting arm and the adjustable stop pins and the roller carried on said roller supporting arm; Fig. 4 is a side elevational view of the structure shown in Fig. 3; Fig. 5 is a top plan view of the twister head plunger actuating cam and hand crank assembly with the hand grip broken away; Fig. 6 is a right side elevational view of the same structure as shown in Fig. 5; Fig. 7 is a top plan view of the base of my machine all moving parts, except the lever actuating plunger, being removed; and Fig. 8 is a vertical sectional view of the structure shown in Fig. 7, the plunger not being sectioned.

Similar characters of reference refer to similar parts and portions throughout the several views of the drawings:

2

My machine is supported on a base 1 which will normally be held in place by attachment screws passed through the screw holes 2. This base 1 may be made with a step portion 3 best shown in Figs. 2 and 7 and referring to Figs. 7 and 8, a boss 4 with an upward extension 4a and a forward extension 4b, and at the front end of the base another boss 5 which is centrally drilled to form a journal indicated at 5a, slotted at the top as at 5b in Figs. 1 and 7, and drilled as at 5c best shown in Figs. 7 and 8.

The wire blank 6, Fig. 1, is shown inserted in my machine, the two ends of the blank passing through the vertical slot 5b and the parts to form 15 the shoulder portions of the hanger are shown bent at the outer ends of the stretcher arms 7 which are pivoted on the base 1 at their inner ends on pins 16a. These arms 7 are forced apart to stretch the wire by a pair of links 9 which 20 actually engage the wire, levers generally indicated at 10 in Fig. 1 and the plunger 11 slidably mounted in the bosses 4 and 5 and forced in a longitudinal direction by cam action when the crank 12 is moved from the starting position 25 shown in Fig. 1 to the second position shown in dotted lines, all as hereinafter described more fully. Simultaneously with this action the forward ends 10b of the levers 10 being suitably shaped for the purpose clamp the wire blank 30 against a forming plate 13 which is rigidly secured to the boss 4 on top of the extension 4a and behind the flange 4b as shown best in Figs. 7 and 8 and in Fig. 1. The plunger 11 does not act directly against the levers 10 but against rollers 10c rotatably mounted by pins 10d on arms 10e which are pivoted to the levers 10 as at 10f. This 35 structure prevents undue friction and wear of the levers and piston and allows for easy adjustment by means of adjustable stop pins 10g, this structure being shown clearly in Figs. 3 and 4 as well as being indicated in Fig. 1. As above stated the plunger 11 is moved longitudinally to spread the levers 10 and passing between said rollers 40 and locking the arms 9 in extended position for holding the wire tight when the crank 12 is turned through 180 degrees in a horizontal plane about the axis pin 12a since this movement carries the eccentric cam 14 pinned to the other end of axis pin 12a into engagement with the 45 forward end of the plunger 11, as will be evident from an examination of Figs. 2, 5 and 6. The relation of the cam 14 with the plunger 11 is shown best in Fig. 2 wherein the plunger 11 is shown by dash lines and designated by the broken 50 leader line in connection with the reference char-

acter 11. Coming now to the twisting of the ends of the wire blank 6, this is accomplished by the rotary head generally indicated at 15 in Fig. 1 and shown in more detailed form in Figs. 5 and 6. This rotary head 15 is rotatably mounted in the journal 5a of the boss 5 being held against movement in the direction of its axis by a pin tightly inserted in a drilled hole at 3c in Fig. 8, this pin engaging the groove 15b in the rotary head. The drilled recess 15c, indicated in dotted lines in Fig. 6 is made to engage the short end of the wire blank as indicated in Fig. 1 while the long end of the wire blank is manually led around the pin 15d as clearly shown in Figs. 1 and 5. A slot 15e in the rotary head corresponding with the slot 5b in the forward boss 5 allows the insertion of the ends of the wire blank when the crank 12 is in the loading position and centrally located of this slot 15e is a smaller slot 15f, Fig. 5, which extends through the opposite side of the rotary head and in the position shown in Fig. 1, the rotary head being locked by a key 11a on the top side of the plunger 11 against turning. This key 11a is forced into the slot 15f by the manual lever 16 shown in Figs. 1 and 2, this lever being pivoted on a pin 16a and being of sufficient length to have its handle section 16b register with the hand grip of the crank 12 when the latter is swung into the locked position. Finally, the hook 17 positionally indicated in Fig. 1 and best shown in Figs. 2 and 6 may be integral with the hub section of the crank 12 and this hook 17 is operative in forming the hook section of the garment hanger. When the crank is moved into the position shown in dotted lines in Fig. 1 this hook 17 rides over the projecting end of the wire blank 6 and when the crank is returned to the starting position the hook 16 preserves a sliding engagement with the wire bending it around the arcuate forming plate 18 in Figs. 2, 5 and 6 which plate 18 is integral with the rotary head 15.

The operation of my machine will be clear from the foregoing. With the rotary head in locked position one end of the wire blank is inserted in the drilled recess 15c of the rotary head, the remainder of the wire being manually placed between the faces 10b of the levers and the forming plate 13 and at the same time around the ends of the links 9, the long end being led out to the twister head and loosely secured thereto between the pin 15d and the arcuate forming plate 18. The crank is then moved horizontally and the cam 14 will move the plunger 11 to force the levers 10 to turn about their axis points 10a bending the wire between the faces 10b of the levers and the forming plate 13 and forcing the links 9 apart so as to stretch the wire blank into the desired shape. With the shoulder bends completed and this part of the wire blank held tightly the next step is to turn the rotary head by means of the crank through two and one-half turns and then return the crank to its original position, the hook 17 bending the wire blank end around the arcuate plate 18 and forming the hook of the garment hanger. As the crank assumes this original position the manual lever 16 is pushed in the same direction as the final movement of the crank and this locks the rotary head in position facilitating the removal of the formed garment hanger and the insertion of the succeeding wire blank and at the same time release the rollers 10c.

Though I have shown and described a particular construction, combination and arrangement of parts and portions, I do not wish to be

limited to this particular construction, combination and arrangement but desire to include in the scope of my invention the construction, combination and arrangement substantially as set forth in the appended claims.

Having thus described my invention, what I claim as new and desire to secure by Letters Patent is:

1. In a device of the character described, the combination of a fixed forming plate, a pair of levers having shaped faces and mounted adjacent said plate, a plunger operably mounted to precisely move said levers toward said plate, roller bearings mounted on said levers to minimize friction between said levers and said plunger, and a rotary head adapted to hold the ends of a wire blank and twist same, and a cam secured to said head adapted to operate said plunger when the cam is rotated.

2. In a device of the character described, the combination of a fixed forming plate, a pair of levers having shaped faces and mounted adjacent said plate, a plunger operably mounted to precisely move said levers toward said plate, roller bearings mounted on said levers to minimize friction between said levers and said plunger, and a rotary head adapted to hold the ends of a wire blank and twist same, a cam secured to said rotary head adapted to operate said plunger when the cam is rotated, and stretcher arms for forming the shoulder bends in the wire blank and operated by links remotely operated by said levers.

3. In a device of the character described, the combination of a fixed forming plate, a pair of levers having shaped faces and mounted adjacent said plate, a plunger operably mounted to precisely move said levers toward said plate, roller bearings mounted on said levers to minimize friction between said levers and said plunger, rotary head adapted to hold the ends of a wire blank and twist same, a cam secured to said head adapted to operate said plunger when the rotary cam is rotated, stretcher arms for forming the shoulder bends in the wire blank and operated by links remotely operated by said levers, a keyway in said rotary head, a key on said plunger and a manual lever to force the plunger away from lever operating position and to insert said key into said keyway temporarily locking said rotary head against turning.

4. In a device of the character described, a rotary head having a recess to carry one end of a wire blank, a pin and an arcuate plate to accommodate therebetween the other or free end 55 of said wire blank, a crank on said rotary head adapted to rotate same thereby twisting the two ends of the said wire together, said crank being pivoted on said rotary head to allow the movement of said crank on a plane parallel to said 60 arcuate plate, a hook on the hub section of said crank adapted to engage the said free end of the wire blank when the crank is moved in one direction before the twisting of the wire is commenced and to bend the said free end around 65 said arcuate plate when the crank is moved in the opposite direction after the twisting action has been completed.

5. In a device of the character described, the combination with a rotatably mounted twister head, of a crank movable on a plane including the axis of rotation of said head, said crank having a cam secured thereto engageable with a plunger, levers actuated by said plunger to extend a pair of arms adapted to form shoulder 75 bends in a wire blank, and a fixed plate positioned

so that said wire blank is doubly bent at the neck portion thereof when portions of said levers move towards said fixed plate when the levers are operated by said plunger.

6. In a device of the character described, the combination with a rotatably mounted twister head, of a crank having a cam engageable with a plunger, levers actuated by said plunger to extend a pair of arms adapted to form shoulder bends in a wire blank, and a fixed plate positioned so that said wire blank is bent at the neck portion thereof by portions of said levers when said portions are moved towards said plate by said plunger.

7. In a device of the character described, the combination with a rotary twister head, of a plunger, a key on said plunger, and a lever to move said plunger so that said key will enter

a keyway in said twister head to temporarily lock the twister head against rotation to facilitate the insertion of a wire blank and the subsequent removal of a formed garment hanger.

8. In a wire garment hanger making machine, a supporting base, linkage means to stretch a wire blank into the desired shape, a plunger to actuate said linkage, a rotary head to twist the ends of said wire blank together, a crank to turn said rotary head, a cam on said crank to operate said plunger, a key on said plunger to engage said rotary head, a lever to move said plunger so that said key will temporarily lock said rotary head, a hook on said crank to engage an end of said wire blank and to bend the same around adjacent structure to form a hook in the wire blank, all substantially as described.

WILLIAM A. SCROGGS.
